EMERGENCY LIGHTING UNIT

Frank D. Shaw, 143 Bermondsey St.,
Toronto, Ontario, Canada

Filed June 29, 1970, Ser. No. 23,702

Term of patent 14 years

Int. Cl. D26—05

U.S. Cl. D48—20

FIG. 1

FIG. 2

FIG. 3

FIG. 4

FIG. 1 is a front perspective view of an emergency lighting unit showing my new design;

FIG. 2 is a front elevation view thereof;

FIG. 3 is a side elevation view thereof; and

FIG. 4 is a partial plan view thereof.

The unit is broken away in FIGS. 1, 2 and 4 to indicate indeterminate length.

I claim:

The ornamental design for an emergency lighting unit, as shown and described.
